No. 618,217.

Patented Jan. 24, 1899.

J. R. ANDREWS.

CLOCK WINDING INDICATOR.

(Application filed May 18, 1898.)

(No Model.)

UNITED STATES PATENT OFFICE.

JOHN R. ANDREWS, OF HOMESTEAD, PENNSYLVANIA.

CLOCK-WINDING INDICATOR.

SPECIFICATION forming part of Letters Patent No. 618,217, dated January 24, 1899.

Application filed May 18, 1898. Serial No. 681,073. (No model.)

To all whom it may concern:

Be it known that I, JOHN R. ANDREWS, a citizen of the United States of America, residing at Homestead, in the county of Allegheny and State of Pennsylvania, have invented 5 certain new and useful Improvements in Clock-Winding Notices; and I do hereby declare the following to be a full, clear, and exact description of the invention, such as will 10 enable others skilled in the art to which it appertains to make and use the same.

This invention is an improvement in clock-winding notices; and the object of the said invention is to provide certain devices which can 15 be readily applied to an ordinary clock and are automatically operated by the mainspring-arbor to raise and lower a sign or indicator that denotes when the mainspring has nearly run down or needs rewinding, the said devices 20 not interfering in any manner with the proper operation of the time mechanism of the clock.

With the above objects in view the invention 25 consists of a vertically-disposed rack-plate supported in suitable guides adjoining the mainspring-arbor, a pivoted arm carrying the indicator suspended therefrom and provided with a short end adapted to bear against the rack-plate, and a finger projecting 30 from the arbor to engage the teeth of said plate, the latter having spaces which permit of a free movement of the arbor after the said plate reaches the limit of its movement in either direction, together with springs acting 35 upon the plate to bring the first tooth at each end in proper engagement with the finger of the arbor.

The following specification enters into a detail 40 description of the invention, and what is claimed as new in the art is more particularly set forth in the appended claims.

In the accompanying drawings, which form a part of this specification, Figure 1 is a front elevation of a clock, showing the application 45 of my invention thereto. Fig. 2 is a front view of my improvements, including only so much of the clock that will show the application of said improvements. Fig. 3 is a detail view of the rack-plate.

With reference to said drawings, A designates 50 guide-brackets which are secured to the front plate B of the casing which supports

the clock-movement, the said brackets being provided with vertical openings and are arranged one above the other adjoining the arbor C, upon which the mainspring of the clock is wound. Sliding loosely in these guide-brackets is a vertically-disposed rack-plate D, having a series of teeth d, and at each end of the series the plate is cut away, as shown, to 60 provide spaces d' for the purpose hereinafter specified. This rack-plate is supported by the frictional engagement therewith of the short end of an arm E, pivoted upon a pin b, projecting from the plate B, the extremity of 65 the longer end of the arm carrying an indicator or notice F, suspended therefrom by a wire or cord f. It will be noted that the shorter end of the arm E bears against one side of the plate near the outer edge thereof 70 and that the gravity of the longer end of said arm, with the parts carried thereby, causes a frictional engagement sufficient only to support the plate, while permitting a sliding movement thereof.

G designates a disk having a square opening by which it is fitted on the squared end of the arbor C, being held thereon by a pin h, and said disk is provided with a projecting finger g, adapted to pass in between the teeth 80 d of the plate D and engage the same. This finger is carried around with the arbor, and by engaging the teeth d gradually raises or lowers the rack-plate, according to the direction said arbor is turned, the plate being moved the 85 space of one tooth at each revolution of the arbor and is supported by the frictional contact of the arm E therewith, as hereinbefore described.

I designate plate-springs which are attached to the clock-plate B and are arranged in such relative position that they engage the ends of the rack-plate D, the upper spring acting against the weight of the arm and indicator to bring the tooth at the lower end of the series 95 in proper position to be engaged by the finger when the movement of the arbor is reversed.

The construction and operation of my improvement will be readily understood from 100 the foregoing description when taken in connection with the accompanying drawings, for upon winding the mainspring the rack-plate D will be lowered and, operating the arm E,

raises the indicator card or notice F to conceal it within the clock, the space d' at the lower part of the rack-plate permitting the arbor to be turned after said plate has 5 reached the limit of its downward movement. Now upon the opposite rotation of the main-spring-arbor in the operation of the time mechanism the rack-plate will be raised by the finger engaging the teeth thereof in succession, and when the lower end of said plate passes above the shorter end of the arm E the longer end thereof will swing downward and move the winding notice or indicator card F into view, the space d' at the lower 10 part of the rack-plate permitting a free rotation of the arbor. Thus it will be observed that the notice or indicator card is brought into view some time before the spring is completely unwound. The plate-springs, which 15 engage the opposite ends of the rack-plate, insure the proper engagement of the finger with the teeth when the direction of rotation of the arbor is reversed.

The parts comprising my improved clock-winding notice are simple and cheap and can be readily applied to an ordinary clock, and when used in connection with the style of clock shown in the drawings the notice or indicator card falls into position to be seen 20 through the glass door covering the space occupied by the pendulum.

Having thus described my invention, what I claim as new, and desire to secure by Letters Patent, is—

35 1. A clock-winding notice, comprising a plate having a series of teeth and wide spaces beyond each end tooth of the series, a pivoted arm one end of which is in frictional engagement with the toothed plate, an indicator-

card carried by the other end of said arm, and 40 a finger projecting from the mainspring-arbor to engage the teeth; together with springs with which the ends of the toothed plate engage, substantially as shown and for the purpose set forth.

2. A clock-winding notice, comprising a toothed plate slidably supported adjoining the mainspring-arbor, said plate having wide spaces beyond each end tooth, an arm pivoted adjoining the toothed plate and presenting 45 a short end which bears against said plate, an indicator-card suspended from the extremity of the longer end of the arm by a wire or cord, and a finger projecting from the mainspring-arbor to engage the teeth of the 50 plate; together with springs with which the ends of the plate engage, substantially as shown and for the purpose set forth.

3. A clock-winding notice, comprising brackets with vertical openings, a plate 55 guided in said brackets and provided with a series of teeth and wide spaces beyond each end tooth of the series, a pivoted arm having a short end bearing against one side of the toothed plate, an indicator-card carried by 60 the other end of said arm, and a finger projecting from the mainspring-arbor; together with springs with which the plate engages at the limit of its movement in either direction, substantially as shown and for the purpose 65 set forth.

In testimony whereof I affix my signature in presence of two witnesses.

JOHN R. ANDREWS.

Witnesses:

II. B. MCCOLLUM,
WALTER DONALDSON.
